UNITED STATES PATENT OFFICE.

FELIX BREIRLY, OF NEW BEDFORD, MASSACHUSETTS.

SKIRT-DRAFTING INSTRUMENT.

1,142,298.

Specification of Letters Patent.

Patented June 8, 1915.

Application filed May 25, 1912. Serial No. 699,770.

To all whom it may concern:

Be it known that I, FELIX BREIRLY, a citizen of the United States, residing at New Bedford, in the county of Bristol and State 5 of Massachusetts, have invented new and useful Improvements in Skirt-Drafting Instruments, of which the following is a specification.

This invention relates to certain new and 10 useful improvements in skirt drafting instruments, and pertains more particularly to an instrument of the type mentioned which is employed to lay out the upper part of the gores of the skirt.

15 The object of the invention is to provide an improved, simple and economical instrument of the type described which can be easily operated and which is capable of ready adjustment to enable gores of varying sizes 20 and shapes to be laid out.

In the drawings, Figure 1 is a top plan view of the invention; Fig. 2 is a section on the line 2—2 of Fig. 1; Fig. 3 is a fragmentary central section at the line 3—3 of Fig. 25 1; and Fig. 4 is a front end elevation.

In accordance with the present invention, one end of an end arm 1, is rigidly secured to a side arm 2, by any suitable means, such as rivets 3. A second side arm 4 is pivoted 30 by means of a pin 5 to the opposite end of arm 1. Arm 4 is slotted at 8 to receive a thumb screw 9 that is carried by a marker 10. The arm 2 has a slot 13 to receive a set screw 14, carried by a marker 11. A pin 12 35 is carried by each marker and projects into the slots of the respective side arms to guide the marker in its sliding movements on said arms, so as to assure the edges 12' of the markers to at all times maintain a right 40 angular relation to the side edges of the side arms. A second end arm 15 is pivoted at 16 to arm 4, and has a curved slot 17 to receive a thumb screw 18, that is carried by the arm 2. Each side arm has a mark "a" thereon 45 adjacent the end arm 1.

The arms 2 and 4 are each provided with scales or graduations, one, for a skirt which requires seven gores, one, for nine gores, and one for eleven gores. The arm 15 is provided 50 with graduations corresponding in number with each of those on the arm 4. In drafting a skirt which is to have nine gores, for a twenty inch waist, and a forty inch hip, marker 10 is moved to the number 20 on the scale 55 that appears in alinement with the number 9, which number indicates the number of

gores the skirt is to have. The marker 11 is then moved to the graduation 40, on the scale in alinement with gore grade 9. The outer ends of the arms 2 and 4, are then adjusted with reference to each other, by means of the thumb screw 18, so that the graduation mark on the arm 15, corresponding with the graduation mark on the arm 4, to which the marker 10 is adjusted, shall be opposite 60 said thumb screw. The instrument is then laid upon the paper of which the pattern is to be made, and chalk lines are made at *a*, *a*, and opposite the points *b*, *b*, on the movable markers 10 and 11. A chalk line is then 65 drawn along the outer edge of the arm 4, and the outer edge of arm 2 between the chalk marks *a*, and *b*. This last named chalk line forms a portion of the circle of the 20 inch waist for which the instrument is set. 70 The instrument is then moved until the edge 20 of the arm 15, coincides with the chalk marks which have been made opposite the points *b*, *b*, and a chalk mark is drawn along the edge thereof connecting the two said 80 marks. This line gives the curve of the skirt gore. By adjusting the instrument correspondingly, a skirt of any stated waist and hip measure may be drafted.

What is claimed is:

1. In a skirt drafting instrument, a pair of spaced opposed side arms arranged in substantially parallel relation, an end arm connected rigidly to one end of one side arm and pivotally connected to the adjacent end 90 of the other side arm, each of said side arms being longitudinally slotted and having a series of scales thereon for different grades of skirts, a marker for each arm, each marker having a guide pin that extends in the slot of the side arm and a thumb screw to hold the marker in any position to which it may be adjusted, a second end arm pivotally connected at one end to the opposite end of one side arm, said second end arm having a 95 curved edge and a slot and having a scale adjacent the slot and corresponding to the scale on one of the side arms, and a thumb screw carried by the opposite side arm and projecting through the curved slot of the second 100 named end arm.

2. In a skirt drafting instrument, a pair of spaced side arms each having a series of scales thereon those on one to indicate the 110 hip and those on the other the waist measurements of different grades of skirts, a marker on each arm for coöperation with the

scales thereof, an end arm connecting said side arms at one of the ends of the latter, and a second end arm adjustably connected to the opposite ends of the side arms and 5 having a scale thereon which scale is similar to a scale on the arm indicating waist measurements.

Copies of this patent may be obtained for five cents each, by addressing the "Commissioner of Patents, Washington, D. C."

In testimony whereof I have hereunto set my hand in presence of two subscribing witnesses.

FELIX BREIRLY.
